UNITED STATES PATENT OFFICE

WILLIAM H. LEE, OF SYRACUSE, NEW YORK, ASSIGNOR TO SYRACUSE CHILLED PLOW COMPANY, OF SYRACUSE, NEW YORK, A CORPORATION OF NEW YORK.

DETACHABLE SHOE FOR LANDSIDES OF PLOWS.

1,073,693.

Specification of Letters Patent. Patented Sept. 23, 1913.

Application filed December 20, 1909. Serial No. 533,997.

To all whom it may concern:

Be it known that I, WILLIAM H. LEE, of Syracuse, in the county of Onondaga and State of New York, have invented a certain 5 new and useful Detachable Shoe for the Landsides of Plows, of which the following is a specification.

My invention relates to plows, and has for its object a detachable shoe or heel-piece for 10 the landsides of plows, and it consists in the combinations and constructions hereinafter set forth and claimed.

In describing this invention, reference is had to the accompanying drawing, in which 15 like characters designate corresponding parts in all the views.

Figure 1 is a side elevation of a plow provided with my invention. Fig. 2 is an enlarged inner face view of the shoe or heel-piece for the landside and contiguous parts. 20 Fig. 3 is a plan of the detached shoe. Figs. 4 and 5 are, respectively, inverted plan and front view thereof.

1 is the frame, 2 the moldboard, 3 the 25 detachable point, 4 the landside, and 5 the brace of my plow, all of which parts may be of any desirable form, size and construction.

6 is the shoe or heel-piece for the landside 4, this shoe being located near the rear end 30 of the landside and having its advance end 6^a spaced apart from the point 3 in a direction lengthwise of the landside and located at the rear of said point 3 the portion of the lower edge of the landside between the point 35 and the advance end of the shoe being normally disposed above the lower supporting faces of said point and shoe, thus causing the plow to bear at two separated points, viz: the point 3 and the heelpiece 6. The 40 shoe 6 is provided with a ledge 7 arranged directly beneath and supporting the lower edge of the rear portion of the landside 4, and with upwardly extending lugs 8, 9 spaced apart from each other, one in ad- 45 vance of the other, the inner faces of these lugs being arranged above, and at substantially a right angle to, the ledge 7 and being designed to engage the inner face of the landside. One of these lugs as the rear lug 50 9 has formed in the surface thereof contiguous to the landside a channel 10 for receiving the lower end of the brace 5, Fig. 2, said brace having its upper end fixed to the inner face of the mold-board.

55 As best seen in Figs. 1 and 2 the shoe is

detachably secured in position by a bolt 11 extending transversely through the front lug 8 and the landside, and an additional bolt 12 extending through the rear lug 9, the lower end of the brace 5 and the landside. 60 By securing the shoe to the landside, as described, a single bolt serves to fasten both the brace and the rear end of the shoe to the landside.

The shoe is formed with a lengthwise laterally extending flange 13, Figs. 1, 3, 4 and 5 of greater length than width for cutting under the unplowed land, the outer side edge of the flange being of materially less length than the base of the flange, the front 65 and rear edges of the flange extending in opposite directions toward the vertical plane of the landside of the plow, said front edge extending forwardly from a point about midway the length of the flange, the upper 70 surface of the flange being concave and converging upwardly toward the outer side of the ledge 7 from substantially the outer side edge of the flange 13, and the flange gradually thickening from its front end toward its 75 rear end, it being the thickest at 14, and the lower face of the flange being flush with the lower face of the contiguous portion of the shoe. The gradual thickening or swelling 80 of the flange from its front end causes the 85 shoe to be forced downwardly into the land and counteracts the tendency of the shoe and landside to raise out of the furrow.

As best seen in Figs. 4 and 5, the shoe 6 is formed with a flat lower face having its 90 front portion decreasing in width toward its front end and extending upwardly toward such end, and is also formed at the inner side of the front end of its lower portion with an undercut substantially lengthwise surface 15 extending rearwardly toward the inner side and lower face of the shoe and also extending rearwardly beyond the rear end of said front portion of the lower face of the shoe. 95

A shoe constructed and arranged as described tends to readily ride over the bottom of the furrow and to deflect by the surface 15 to the inner side of the landside, any stones, loose earth, etc., which would otherwise tend to lift the rear end of the plow and thus effect an undesirable change in the position thereof. Said shoe is thus particularly advantageous in that it relieves the landside of most of the wear thereon, may 105 110

be easily removed and replaced at small expense and facilitates the maintenance of the position of the plow.

What I claim is:—

5. 1. In a plow, a point, a landside, and a shoe detachably secured to the landside near the rear end thereof and having its advance end spaced apart from the point of the plow in a direction lengthwise of the landside, 10 said shoe having a lower supporting face arranged directly beneath the lower edge of the overlying portion of the landside and extending on opposite sides of the vertical plane of the outer face of the landside, a portion of the lower edge of the landside between the point of the plow and the advance end of the shoe being normally disposed above the plane of a portion of said lower supporting face of the shoe, substantially as and for the purpose described: 15
2. In a plow, a mold-board, a landside, a shoe for the landside, said shoe being provided with an upwardly extending lug contiguous to the inner face of the landside, 20 and a brace having one end fixed to the inner face of the mold-board and its other end interposed between opposing faces of the landside and the lug, and fixed to said landside and lug, substantially as and for the purpose specified: 25
3. In a plow, a point, a mold-board, a landside, a shoe provided with a ledge arranged directly beneath and supporting the lower edge of the rear portion of the landside, the shoe being also provided with lugs spaced apart from each other in a direction lengthwise of the landside and extending upwardly above the ledge and engaging the inner face of the landside, the surface of the 35 rear lug contiguous to the landside being formed with a channel, said shoe having its advance end spaced apart from the point in a direction lengthwise of the landside, and a portion of the lower edge of the landside between the point of the plow and the advance end of the shoe being disposed above the plane of lower supporting faces of said point and shoe, a brace having one end fixed to the inner face of the mold-board, and its 40 other end arranged in said channel, means for securing the front lug to the landside, and a fastening member for securing the rear lug and the contiguous end of the brace to the landside, substantially as and for the 45 purpose set forth: 50
4. In a plow, a landside, and a shoe for the landside, the shoe having on its outer side a lengthwise laterally extending flange of greater length than width for cutting under the unplowed land, the front edge of said flange converging forwardly toward the vertical plane of the landside from a point about midway the length of the flange, substantially as and for the purpose described: 55
65. 5. In a plow, a landside, and a shoe for

the landside, the shoe having on its outer side a lengthwise laterally extending flange for cutting under the unplowed land, the front edge of said flange converging forwardly toward the vertical plane of the landside, and an upper surface of said flange converging upwardly toward said plane of the landside from substantially the outer side edge of the flange, substantially as and for the purpose specified. 75

6. In a plow, a landside, and a shoe provided with a ledge arranged directly beneath and supporting the lower edge of the rear portion of the landside, the shoe being also provided on its outer side with a lengthwise laterally extending flange of greater length than width for cutting under the unplowed land, the outer side edge of the flange being of materially less length than the base of the flange, and the upper surface of said flange converging upwardly toward the outer side edge of the ledge, substantially as and for the purpose set forth. 80

7. In a plow, a landside, and a shoe provided with a ledge arranged directly beneath and supporting the lower edge of the rear portion of the landside, the shoe being also provided on its outer side with a lengthwise laterally extending flange for cutting under the unplowed land, the ends of the flange extending in opposite directions from the outer side edge of the flange toward the vertical plane of the landside, and the upper surface of said flange converging upwardly toward the outer side edge of the ledge, substantially as and for the purpose described. 90

8. In a plow, a landside, and a shoe for the landside, the shoe having the inner side of the front end of its lower portion formed with an undercut substantially lengthwise surface diverging rearwardly relatively to the outer side of the shoe for deflecting particles of earth to the inner side of the shoe, substantially as and for the purpose specified. 105

9. In a plow, a landside, and a shoe for the landside, the shoe having the inner side of the front end of its lower portion formed with an undercut substantially lengthwise surface extending rearwardly toward the inner side and the lower face of the shoe for deflecting particles of earth to the inner side of the shoe, substantially as and for the purpose set forth. 115

10. In a plow, a landside, and a shoe for the landside, the shoe having the front portion of its lower face extended upwardly toward the front end of the shoe, said shoe also having the inner side of the front end of its lower portion formed with an undercut substantially lengthwise surface diverging rearwardly relatively to the outer side of the shoe for deflecting particles of earth to the inner side of the shoe, said length- 125

wise surface extending rearwardly beyond the rear end of said upwardly extending front portion of the lower face of the shoe, substantially as and for the purpose described.

11. In a plow, a landside, and a shoe for the landside, the shoe having a substantially flat lower face decreasing in width toward its front end and extending upwardly toward such end, said shoe also having the inner side of the front end of its lower portion formed with an undercut substantially lengthwise surface extending rearwardly toward the inner side and the lower face of the shoe for deflecting particles of earth to the inner side of the shoe, substantially as and for the purpose specified.

12. In a plow, a point, a mold-board, a landside, a shoe provided with a ledge arranged directly beneath and supporting the lower edge of the rear portion of the landside, the advance end of the shoe being spaced apart from the point of the plow in a direction lengthwise of the landside, and a portion of the lower edge of the landside between the point of the plow and the advance end of the shoe being normally disposed above the plane of lower supporting faces of said point and shoe, the shoe be-

ing also provided on its outer side with a 30 lengthwise laterally extending flange for cutting under the unplowed land, the front edge of said flange converging forwardly toward the vertical plane of the landside, and an upper surface of said flange converging upwardly toward the outer side edge of the ledge from substantially the outer side edge of the flange, and the shoe having a substantially flat lower face decreasing in width toward its front end and 40 extending upwardly toward such end, said shoe also having the inner side of the front end of its lower portion formed with an undercut substantially lengthwise surface extending rearwardly toward the inner side 45 and the lower face of the shoe for deflecting particles of earth to the inner side of the shoe, substantially as and for the purpose set forth.

In testimony whereof, I have hereunto 50 signed my name in the presence of two attesting witnesses, at Syracuse, in the county of Onondaga, in the State of New York, this 16th day of December, 1909.

WILLIAM H. LEE.
